UNITED STATES PATENT OFFICE

PASCAL SBURLINO, OF DAYTON, OHIO, ASSIGNOR TO THE NATIONAL CASH REGISTER COMPANY, OF DAYTON, OHIO, A CORPORATION OF MARYLAND

CASH REGISTER

Application filed March 1, 1929. Serial No. 343,665.

This invention relates to improvements in key release mechanisms for cash registers and the like, and is more particularly directed to the type shown and described in United States Letters Patent, issued to B. M. Shipley, No. 1,619,796, on March 1, 1927 and No. 1,602,596, on October 12, 1926.

As illustrated in the foregoing patents, there is provided a keyboard comprising a plurality of rows of amount determining keys for use in setting up the amounts to be registered, and one or more rows of totalizer selecting keys to enable the operator to select the particular totalizer or totalizers on which the items set up on the amount keys are to be accumulated.

Suitable and well-known mechanism is provided to latch or detain the depressed keys in their set positions, which key-detaining mechanism is actuated near the end of the operation of the machine to release the depressed keys, so that they may restore to their normal positions preparatory to the next operation of the machine.

It is also customary to provide a lock for the drive mechanism of the machine which prevents operation of the machine until a special key is depressed to release such machine lock.

Conveniently, the detent-releasing mechanism for the keys of the keyboard is combined with the machine lock releasing mechanism, it being necessary to depress the special key to release the machine lock. Simultaneously with and incident to the release of the machine lock, the detent-releasing mechanism for the keys of the keyboard is shifted in one direction to lock the detents against movement and thereby prevent restoration of the depressed keys or depression of any keys at that time in normal position. Then, near the end of the operation of the machine, the detent-releasing mechanism is shifted in the opposite direction to release the key detents and enable any depressed keys to restore to their normal positions. At the same time, the machine lock is restored to effective position, after which the detent locking and releasing mechanism returns to

its normal home position intermediate its extreme limits of movement.

Obviously, the operation of the detent-releasing means near the end of each operation of the machine to enable the depressed keys to restore, necessitates re-depression of the keys in setting up a second amount to be accumulated in the machine, but it is sometimes desired to add the same identical amount a number of times successively.

This result has generally been effected in the prior art, by providing a special key, depression of which disables the detent-releasing mechanism to prevent it from shifting the key detents so that the depressed keys representing the amount to be again added, will be held in their depressed positions.

But in the present machine, due to the combination of the machine-locking mechanism with the detent-releasing mechanism, such disabling of the detent-releasing mechanism would be undesirable, because it would necessitate the provision of a more or less complicated means to insure the efficiency of the machine-release lock, and to guard the detent-release mechanism against improper operation.

Therefore, one of the objects of this invention is to equip a machine with novel means whereby amounts set up on the keyboard may be repeatedly added, by the retention of the depressed keys in depressed position, or whereby different amounts may be successively added, at the will of the operator and without changing the normal relations between the machine lock and detent release mechanisms.

To accomplish this object, the control of the detent-releasing mechanism is removed from the special machine-lock-releasing key, and is vested in a second special key, as a result of which arrangement, the release of the machine lock through the first-named special key permits an operation of the machine, without operating the detent-releasing mechanism to release the keys, so that the depressed keys remain depressed at the end of an operation preparatory to the repeated accumulation of the amount represented thereby.

- But since it is desired that the machine be able to handle different amounts or items successfully, the machine is so contrived that depression of the second-named special key 5 renders the detent-release mechanism effective so that the depressed keys will be freed to the action of their restoring means, at the end of each operation of the machine thus initiated.
- 10 The second-named or non-repeat special key is located, in the present instance, at the left hand side of the keyboard where it may not be as conveniently and quickly depressed, and as much of the work performed on machines of this type does not require the repeated accumulation of the same item, another object of the invention is to provide means which will enable the operator to use the first-named or repeat special key to release the machine for operation and yet effect the restoration of the depressed amount keys at the end of the operation.
- 15 With these and incidental objects in view, the invention consists of certain novel features of construction and combinations of parts, the essential elements of which are set forth in appended claims and a preferred form or embodiment of which is hereinafter described with reference to the drawings 20 which accompany and form part of this specification.

In the drawings:

- 55 Fig. 8 is a cross sectional view taken to the right of one of the amount banks and differential mechanisms, showing the key detents and the means to shift the detents relatively to the keys.

GENERAL DESCRIPTION

The well-known machine to which the present invention is shown applied, is pro-

vided with the usual keyboard, including amount banks of keys, to control the respective differential mechanisms for entering the various amounts or items set up on the keyboard, into the machine. The present invention provides means whereby repeat operations can be effected without necessitating the operation of a special repeat key in addition to the machine release key. Any amount can be set up on the keyboard by depressing the proper amount keys and the machine released for operation by depressing the machine release key at the right hand side of the machine.

In this invention, the usual detent release mechanism for the amount keys is normally ineffective for releasing the keys during the operation of the machine, and therefore, the same amount can be repeated by merely again pressing the above-mentioned machine release key.

A second machine release key has been provided for releasing the machine when it is desired to enter an amount only once, that is, when entering different amounts successively. Depression of such second machine release key operates to couple the detent-releasing device to its operating mechanism so as to effect the release of the depressed amount keys near the end of the operation of the machine.

It is often desirable to enter a number of different amounts successively, and it is apparent that, in general, the right hand machine release key is the most convenient to use for releasing the machine. Therefore, a special key is provided, which, upon being depressed, will couple the detent-releasing mechanism with the machine release controlled by the right hand machine release bar, so that upon operation of such bar, with the special key in its depressed position, the amount key release mechanism will be operated to enable the amount keys to restore to normal near the end of each operation of the machine initiated by the depression of the right hand machine release bar.

This special key is located adjacent the left hand machine release bar and is preferably what is known in the art as a stay-down key, that is, this key will remain in its depressed position indefinitely. The special key is only releasable near the end of an operation of the machine which as been initiated by depression of the left hand machine release key.

DETAILED DESCRIPTION

Keyboard

As shown in Fig. 1, the machine is provided with six banks of amount keys 30, of the well known type shown and described in the above mentioned patents. The machine is also provided with a bank of clerks' keys 31, a bank of department keys 32, and a bank of special

transaction keys 33. The function of the three control banks 31, 32 and 33, forms no part of the present invention, and therefore, no further mention thereof will be made herein.

The machine is also provided with a machine lock releasing key 34, (Figs. 1 and 6) conveniently located to the right of the control bank of keys. This machine lock releasing key will be referred to as the "repeat" lock releasing key.

The usual total lever 37 is located between the row of transaction keys 33 and the right hand or "repeat" machine release key 34, to control the machine for total taking operations.

The machine is also provided with a series of ledger number keys 38 for use in printing designating numbers, which are not accumulated. The ledger number keyboard and the printing mechanism encased in the extension 39 of the cabinet, form no part of the present invention, and will not be further mentioned.

Operating mechanism

The machine can be operated either by an electric motor (not shown) or by the operating handle 45 (Figs. 1 and 6) sleeved to a pinion 47 meshing with a gear 48 which drives a gear 49 secured to the main cam or drive shaft 50. The ratio of the gears is such that two complete operations of the handle 45 will effect one complete rotation of the drive shaft 50.

Key banks

The denominationally arranged amount keys 30 (Fig. 8) are slidably mounted in key frames 46, supported on cross rods 51 and 52, extending between the side frames 58 and 59 (Figs. 8 and 6) of the machine, in the usual and well known manner. Each key is provided with a pin 53 which, upon depression of the key, cooperates with the usual shiftable detent bar 54 associated with that row in which the key is depressed, to hold the key in its depressed position. Links 57, only one of which is shown, pivotally support the detent bar 54 at its opposite ends, and a spring (not shown) holds the detent bar in, and returns it to, its normal position. Depression of a key 30 presses its pin 53 against the corresponding beveled hook of the detent bar 54 to cam the detent bar downwardly until the pin 53 passes below the bill of the detent hook, whereupon the spring will restore the detent bar to its normal position with the hooked portion thereon above the pin 53.

The operator depresses the amount keys corresponding to the amount desired to be entered in the machine, and then operates the machine to effect the registration of such amount.

Machine release mechanism

It is customary, as fully set forth in the patents mentioned at the beginning of the specification, to provide means to normally lock the machine against operation.

Such lock includes a detent 91 (Fig. 3) journaled on a suitably-supported shaft 92, a spring 127 holding the free end of the detent in the path of a stud 89 projecting laterally from a locking arm 90 fast on a release shaft 56 journaled in the opposite side frames 58 and 59.

The release shaft 56, at a point adjacent the side frame 59 (Fig. 6), carries an arm 88 having a stud 87 projecting into a slot 126 in a link 86. This link also has formed therein an opening 84 through which projects a pin 124 carried by an arm 122 journaled at 123, to support the link. A strong spring 85 mounted on pilots in the slot 126, presses upwardly against the stud 87 of the arm 88 on the release shaft 56, to rock the latter clockwise.

But the operation of the release shaft 56 by the spring 85 is normally prevented by the contact of the locking detent 91 (Fig. 3) with the locking arm 90.

This lock is controlled from the machine release key 34, removably mounted on the usual slide 100 slotted to accommodate the guide pins 101 which hold it to the side frame 59.

A pin 103 (Fig. 7) on the slide seats in a bifurcation at one end of an intermediate lever 104 pivotally supported on a stud 105, the opposite end of the intermediate lever 104 carrying a pin 106 entered in a bifurcation formed in the arm 107 of a bail 109 journaled on the shaft 92.

The remaining arm 108 of the bail 109 is hooked to take over a stud 110 on the arm 114 of a second bail 112 journaled on the release shaft 56, the remaining arm 111 of such second-named bail 112 being forked to engage a stud 113 on the machine locking detent 91.

Obviously, depression of the machine release key 34 and its slide 100, will rock the intermediate lever 104 against the tension of its restoring spring 115, and the lever 104, through bails 109 and 112, will displace the locking detent 91 from the path of the stud 89 on the locking arm 90 fast on the release shaft 56.

Thereupon the spring 85 (Fig. 6) rocks the arm 88 and release shaft 56 clockwise to one limit of its travel, the stud 87 being shifted to the upper end of the slot 126 in the link 86.

In motor driven machines, the release shaft 56 operates to trip the clutch detent and free the motor for operation, as shown in patent to Shipley, No. 1,619,796, referred to, the motor turning the drive shaft 50 through one rotation, as also shown in such patent.

In crank-operated machines, the operator, after depressing the release key 34, actuates

the handle 45 through two rotations, which, through the train of gears 47, 48 and 49, imparts a single rotation to the drive shaft 50.

Differential mechanism

5. Each denominational bank or row of amount keys 30 controls its differential mechanism (Fig. 8) to effect the entry of the amounts set up on the keyboard into any one 10 or more selected totalizers 60. Since this mechanism is well known in the art and is described in detail in the above mentioned patents, only a very brief description will be given herein.
15. Three lines of totalizers 60 are shown into any unit of which the amount set up on the keyboard may be entered. Each differential mechanism includes an actuator 61, differentially positioned under control of the depressed keys.

20. A series of cams 62 are arranged in pairs on the drive shaft 50, one pair for each actuator 61. Each pair of cams 62 positively rocks its suitably pivoted bell crank lever 63, 25 first clockwise and then counter-clockwise during a single rotation of the drive shaft. Links 65 connect the several bell crank levers 63 with their respective drivers 64 journaled in hangers 68 supported at intervals between 30 the side frames 58 and 59.

25. A latch 79 pivotally mounted on each actuator 61, connects its actuator to the corresponding driver 64. This connection causes the actuator 61 to be turned clockwise when 35 the driver is operated by the cams 62, until the latch strikes the inner end of the depressed key 30, whereupon the latch 79 is disengaged from the driver and the differential actuator is arrested in a position corresponding with 40 the value of the particular key depressed.

45. After the actuator 61 has been positioned, the selected totalizer or totalizers 60 are shifted into engagement therewith, whereupon the actuator is returned to its normal or home position by the driver 64, in a manner well known in the art. This return movement of the actuator 61 enters the amount on the various totalizers which have been engaged therewith.

50. A zero stop pawl 65 is provided for each actuator, which pawl normally lies in the path of a trip arm 67 connected to the latch 79, to disengage the latch, and hence its actuator, from the associated driver 64 when 55 no key 30 is depressed in that key bank. Depression of a key 30 shifts a release bar 66 connected by means, not shown, to the zero stop pawl 65 to rock the latter to its ineffective position. This mechanism is well known in the art and no further description thereof is thought necessary.

60. The differential positioning of the actuators 61 is transmitted to the indicating and printing mechanisms through the usual and well known beams 70, pivoted at their for-

ward ends to the respective actuators, and bifurcated at their rear ends to embrace studs 69, mounted on connecting links 71 to adjust the latter according to the values of the keys depressed.

65. These links 71 are connected at their upper ends to segments 72, adapted to adjust mechanism, not shown, for indicating the amount set up on the keyboard, and at their lower ends, the links 71 are connected to arms 73 fast 75 with spiral segments 74 journaled on a cross shaft 75 and meshing with spiral gears 76 secured to the individual shafts 77 to set type wheels (not shown) for printing the amounts set up on the keyboard. This mechanism 80 forms no part of the present invention, and therefore, no further reference thereto will be made.

85. Near the end of the operation of the machine, the release shaft 56 (Fig. 6), is restored to its normal intermediate position by a cam race 120, formed in the side of the before-mentioned gear 48. It will be noted that the cam race 120 has two camming portions, because the gear 48 receives only one-half rotation for each adding operation of the machine, and therefore, the camming portions of the race will alternately operate to restore the release shaft 56.

90. The supporting arm 122 for the link 86 carries a roller 121 adapted to traverse the cam race 120 in the gear 48. The stud 124 on the supporting arm normally lies in a notch offset from the opening 84 (see Fig. 6), in the link 86, and the provision of the roll 121 in 100 the cam race 120 prevents the arm 122 from yielding in clockwise direction under the tension of the spring 85. When the gear 48 nearly completes a half rotation, the cam portion of the cam race 120 operates upon the roller 121 of the supporting arm 122 to rock the arm downwardly in clockwise direction and draw the link 86 downwardly to its opposite limit of movement, after which the cam race restores the arm 122 to its normal 110 position.

115. At the time when the cam portion of the race 120 acts upon the arm 122, the stud 87 of the arm 88 lies at the upper end of the slot 126 in the link, so that the link 86 will rock the arm 88, together with the release shaft 56 counter-clockwise to the opposite limit of its travel, and then restore the release shaft and its locking arm 90 to their normal positions intermediate their limits of travel. The spring 127 rocks the detent 91 into the path of the stud 89 on the locking arm 90, as the release shaft 56 passes its normal intermediate position in counter-clockwise direction, to arrest and lock the arm 90 and the release shaft 56 in their normal positions to prevent operation of the machine.

Control of key release mechanism

120. Also near the end of the operation of the 130

machine, i. e., the single rotation imparted to the drive shaft 50 in adding amounts, it is desirable, when listing successive amounts differing from each other, to effect the release of the depressed keys, so that they may return under the influence of the usual springs (not shown) to their normal undepressed positions preparatory to the succeeding operation.

10 To release the depressed keys 30, it is necessary to shift the detent bars 54 downwardly far enough to disengage the hooked portions thereof from the pins 53 of the depressed keys. This is effected by the bail 55 (Fig. 8), 15 the arms of which are loosely mounted on the machine release shaft 56, the bail 55 being rocked in counter-clockwise direction to contact the arms 78 (Fig. 8) of the detent bar supporting links 57 and rock them in clockwise direction, thereby lowering the detent bars 54 and releasing the depressed keys 30.

20 But occasionally, it is desired to enter the same amount a number of times successively in the machine, as in making up pay rolls, 25 multiplying by repeated addition and for other purposes.

And the invention herein set forth relates particularly to means to facilitate the restoration of depressed amount keys at the end 30 of a single operation, or their retention in depressed positions throughout a plurality of operations.

Heretofore, the release shaft 56 on its counter-clockwise travel, has been utilized to 35 shift the key detent bars 54 to idle position to free the depressed keys for restoration, by a suitable bail fast on the release shaft, adapted to contact the usual rearwardly projecting arms 78 of the upper links 57 and cam the detents downwardly.

40 In the present invention, changes have been made in the forms and functions of this and other features, a preferred embodiment of 45 which will be now set forth.

The machine release key 34 of the present invention corresponds to the so-called motor bar of Shipley's Patent, 1,602,596, heretofore referred to, to effect the release of the detent 50 which locks the machine against operation.

In the present machine depression of the release key 34 will release the machine for operation, and the operation will take place without releasing the key-detent bars 54.

55 Therefore, the keys 30 which have been depressed, will remain depressed at the completion of the operation, and by again depressing the machine-release key 34 and operating the machine, the former amount set up on the keyboard will be again entered in the machine, such repeated entry occurring as often as the machine release key 34 is depressed.

60 For this reason, the machine release key

34 is called the "repeat" release key.

Non-repeat key machine release

In order to enable the operator to enter different amounts successively into the machine, a second machine lock releasing key 70 35 (Figs. 1 and 2) is mounted on the keyboard, which is called the "non-repeat" release key, depression of which operates to release the machine for operation.

This "non-repeat" key 35 is preferably located at the left of the bank of amount keys of highest value, and is equipped with a stud 130 (see also Fig. 3) which, in the present instance, extends through and projects from each side of the key shank. When the non-repeat machine release key is depressed, the left hand end of the stud 130 contacts the forward arm of a lever 131, pivoted on a stud 132 mounted in the frame of the machine. 75 The rear arm of the lever 131 is bifurcated to embrace a stud 133 carried by the left hand arm of a yoke 134 journaled on the release shaft 56. The yoke 134 extends across the entire amount keyboard, and is provided 80 at its right hand end with an arm 135, adapted to contact the before-mentioned stud 113 on the locking detent 90.

Hence, depression of the "non-repeat" machine release key 35 will displace the locking 85 detent 91 from the path of the stud 89 on the locking arm 90, to release the machine for 90 operation.

Amount key release

100 As before mentioned, the detent bar releasing bail 55 is journaled on the release shaft 56, and hence will not ordinarily be rocked by the shaft when the latter is turned in counter-clockwise direction past its normal position during the operation of the machine, and the amount keys will remain in their depressed positions. However, depression of the "non-repeat" release key 35 operates means to couple the release bail 55 with 105 the release shaft 56 in the following manner.

The forwardly extending arm of the lever 131, which is rocked in counter-clockwise direction by the "non-repeat" release key 35, as above described, carries a stud 140, adapted 110 to contact the shoulder 139 of a depending control arm 141 (Figs. 2, 3 and 4) pivoted on the stud 132 in the key frame. The control arm carries a roller 142 at its free end, with which the arcuate edge of a coupling 115 slide 143 contacts under the influence of a spring 144, coiled around the release shaft 56 and having each end thereof connected with the coupling 143. The coupling slide 143 is radially slotted to embrace the release shaft 120 56 and slide radially thereof, the shaft 56 being kerfed at diametrically opposite points to accommodate the coupling 143, and cause the coupling to turn with the release shaft, 125 as shown in Fig. 4.

Depression of the "non-repeat" release key 35 rocks the control arm 141 counter-clockwise against the coupling 143 to shift the latter farther over the shaft 56.

5 The coupling 143 carries a stud 145 (Figs. 2 and 4) which, when the coupling 143 is in its normal idle position, lies beyond the path of travel of an arm 146 of the detent-releasing bail 55 for the amount keys.

10 But, upon depression of the "non-repeat" release key 35, the control arm 141 forces the coupling slide 143 farther over the release shaft 56 against the tension of the disengaging spring 144, to position the coupling stud

15 145 in the path of the arm 146. With the "non-repeat" release key 35 depressed to release the locking detent 91, and maintain the coupling 143 effective, the release shaft 56, when rocked in clockwise direction at the beginning of the operation of the machine, by the spring 85, as heretofore explained, will merely carry with it the coupling slide 143 to swing the coupling pin 145 away from the arm 146 of the detent release bail 55.

20 25 Then, on the counter-clockwise rotation of the release shaft 56, imparted thereto by the cam race 120, (Fig. 6), restoring arm 122 and link 86 as heretofore described, the coupling stud 145 (Figs. 2 and 4) will contact the arm 146 of the bail 55, and rock the bail in counter-clockwise direction to its opposite limit of travel. On this counter-clockwise travel of the bail 55, it strikes all of the arms 78 (Fig. 8) of the detent-supporting links 57 for the 30 amount banks of keys, and shifts the detents 35 54 to release the depressed keyes, as before described.

30 40 A detent bar 150 (Figs. 2 and 5) supported at its opposite ends by links 152 and 153, carries a hook 149 to take over the stud 130 on the "non-repeat" key 35 and hold it in its depressed position. A spring 151 normally tends to urge the detent bar 150 upwardly, but upon depression of the "non-repeat" key, 45 its stud 130 cams the detent bar downwardly until the stud passes the bill of the hook, whereupon the spring 151 restores the detent bar to position the hook 149 above the stud 130.

50 55 A spring (not shown) normally holds the "non-repeat" key 35 in its outer or undepressed position. Therefore, when the bail 55 engages the rearwardly extending arm of the link 153 to shift the detent 150 to idle position, the "non-repeat" key 35 will be released and will restore to its normal undepressed position.

60 65 A coiled spring 160 (Fig. 5) holds the release bail 55 in its normal position at the clockwise limit of its travel. One end of the spring 160 is connected to the release bail 55 and the other end to a stationary bracket 161, mounted on the release shaft 56 and the shaft 92. The upper end of the bail 55 contacts a 70 stop shoulder 162 on the bracket 161.

When the bail 55 is coupled to the release shaft 56 through the coupling 143, and the release shaft is operated, the bail 55 is rotated in counter-clockwise direction against the tension of the spring 160 near the end of the operation of the machine. When the release shaft 56, at the end of its operation, returns to its normal position intermediate the ends of its path of travel, in clockwise direction, the spring 160 will cause the bail 55 to return to its normal position.

Converting the "repeat" release key into a "non-repeat" release key

As heretofore stated, it is easier for a right-handed operator to actuate the release key 34 than the key 35. Hence, where the work to be performed on the machine involves the entry of a succession of different items on successive operations of the machine, means is provided to enable the operator to adjust the mechanism so that the "repeat" release key 34 will act as a "non-repeat" release key. To this end, a special key 36 (Figs. 1, 2 and 4) is provided, which, upon being depressed, couples the amount key release mechanism to the machine release mechanism so that the machine can be released by depression of the repeat release key 34 for operation when it is desired to enter an amount only once.

The special key 36 controls the coupling 143 so that the amount and transaction keys will be restored at the end of each adding operation of the machine, when the machine has been released by the usual "repeat" release key 34. The key 36 is a "stay-down" key and once depressed, it remains in depressed position until the machine is released for operation by the left hand or "non-repeat" key 35.

The special key 36 carries a stud 170 (Figs. 2 and 4) which cooperates with an inclined projection 171 on a control bar 172, pivotally connected at its upper end to the coupling control arm 141, and at its lower end to a supporting link 173. Depression of the special key 36 shifts the control bar 172 clockwise against the tension of a spring 174, to rock the control arm 141 against the coupling 143 in exactly the same manner as when actuated by the "non-repeat" key 35, to slide the coupling farther onto the release shaft 56 and introduce the coupling stud 145 into the path of the arm 146 (Fig. 2) of the detent-release bail 55. Thus, when the repeat key 34 is operated, the special key 36 being in its depressed position, the detent-release bail 55 will be operated by the release shaft 56 on its counter-clockwise travel, to displace the detent bars 54 and release all of the depressed keys 30.

A retaining hook 175 (Fig. 2), projecting from a detent bar 169, cooperates with the stud 170 of the special key 36, to retain the key in depressed position. The detent bar

169 is pivotally supported at one end by a link 176, the opposite end of the detent bar 169 having a pin 177 which projects into a slot 178 in the control bar 172, to permit relative movement of the detent bar and control bar independently of each other.

The detent bar 169 is not operable by the detent release bail 55, and therefore, other means is provided to release the special key

10 36. Conveniently such release of the special key is effected by the "non-repeat" key 35. The detent bar 169 has an upwardly extending cam 179, with which cooperates the stud 130 on the non-repeat release key 35. When 15 the "non-repeat" key 35 is depressed, the stud 130 wipes along the cam 179 to shift the detent bar 169 counter-clockwise, thereby disengaging the detaining hook 175 from the stud 170 of the special key 36 to free the latter for restoration to normal position.

Spring 180 wound around a stud 181 of the key frame and upon which the links 152, 173 and 176 are mounted, tends to hold the 25 detent bar 169 in and return it to its normal position with the stud 177 at the upper end of the slot 178 in the control bar 172.

Operation

30 The operation of this invention has been heretofore explained, but briefly recapitulated, when the operator desires to repeatedly enter the same amount, he will depress the proper amount keys 30, and select the totalizers by depressing the control keys 31, 32 and 33, after which he depresses the "repeat" release key 34 and the machine is operated. During such operation, the amount is entered 40 in any one or more of the various totalizers, and at the end of the operation, the amount keys 30 remain in their depressed positions, because the release bail 55 is not coupled with the key release shaft 56.

45 If it is desired to enter an amount only once, the operator depresses the proper amount keys 30 and selects the totalizer or totalizers, as before, after which he releases the machine by depression of the "non-repeat" key 35. Depression of this key 35 couples the key release bail 55 to the release shaft 56, so that near the end of the operation of the machine, the bail 55 will be operated to release the amount keys.

50 When it is desired to enter a great many different amounts, each of which is to be entered only once, the key release bail can be controlled from the "repeat" motor key 34, by depression of the special key 36, which 60 couples the key release bail 55 to the key release shaft 56, so that during the operation of the machine, when released by the "repeat" motor key 34, the bail 55 will be effective to release the depressed amount 65 keys.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed as new, is:

1. In a machine of the class described, the combination with depressible keys; and a detent to maintain the keys depressed; of a normally ineffective device adapted to actuate the detent during the operation of the machine to free the depressed keys; normally locked operating mechanism; means to release the operating mechanism for an operation during which the detent actuating device remains ineffective and the keys remain depressed; a second independently operable means to release the operating means for operation; an adjustable member operable by the depression of the last-named release means; and a coupling device adapted to be operated by the adjustable member to couple the normally ineffective detent actuating device with the operating mechanism to cause the device to become effective during an operation of the machine.

2. In a machine of the class described, the combination with depressible keys; a detent to maintain the keys depressed; a normally ineffective member to actuate the detent during the operation of the machine to free the keys; normally locked operating mechanism; a machine release key to release the normally locked operating mechanism for an operation during which the detent-releasing member remains ineffective and the keys remain depressed; a second machine release key to release the operating mechanism for operation; a control operable by the depression of the second-named machine release key; a coupling device adjustable by the control and operated by the operating mechanism; a projection on the coupling device; and an arm on the normally ineffective detent-actuating member adapted to lie in the path of the projection of the coupling device when said coupling device is adjusted by the second-named machine release key.

3. In a machine of the class described, the combination with depressible keys; a detent to maintain the keys depressed; a normally ineffective member to actuate the detent during an operation of the machine to free the keys; normally locked operating mechanism; a machine release key to release the machine for an operation during which the detent-actuating member remains ineffective, and the keys remain depressed; a special key; a sliding control bar adjustable by the special key; a control member adjusted upon opera-

tion of the slidable control bar; and a coupling device operable by the control member to couple the normally ineffective detent-actuating member with the operating mechanism to render the detent-actuating member effective during an operation of the machine.

4. In a machine of the class described, the combination with depressible keys; a detent to maintain the keys depressed; a normally ineffective member to actuate the detent during the operation of the machine and free the keys; normally locked operating mechanism;

10 a machine release key to release the normally locked operating mechanism for an operation during which the detent-actuating member remains ineffective, and the keys remain depressed; a special key; a slidable control bar adjustable by the special key; a control member adjusted upon operation of the slidable control bar; a slidable coupling device adjustable by the control member, and operated by the operating mechanism; a projection on the coupling device; and an arm on the normally ineffective detent-actuating device

15 20 25 adapted to be engaged by the projection of the coupling device when said coupling device is adjusted to effective position by the special key.

5. In a machine of the class described, the combination with a normally locked operating means; depressible keys; and means to detain the keys in their depressed positions; of a normally ineffective means to actuate the detaining means and free the depressed keys; means to release the normally locked operating means to enable an operation of the machine during which the actuating means for the key-detaining means remains ineffective; and a second means to release the normally locked operating means, and render effective the actuating means for the key-detaining means.

6. In a machine of the class described, the combination with a normally locked operating means; depressible keys; and means to detain the keys in their depressed positions; of a normally ineffective means to actuate the detaining means and free the keys; means to release the normally locked operating means to enable an operation of the machine during which the actuating means for the key-detaining means remains ineffective; a second means to release the normally locked operating means; and means controlled by such second-named machine-releasing means to couple the actuating means for the detaining means with the operating means.

7. In a machine of the class described, the combination with operating mechanism; depressible keys; and means to detain the keys in their depressed positions; of normally ineffective means to actuate the key-detaining means and free the keys; a plurality of manipulative means to control the operation of the operating mechanism; and a coupling

device controlled by one of the manipulative means to couple the normally ineffective actuating means with the operating mechanism.

8. In a machine of the class described, the combination with operating mechanism; depressible keys; and means to detain the keys in their depressed positions; of normally ineffective means to actuate the key-detaining means to free the depressed keys; a plurality of manipulative means to control operation of the operating mechanism; a coupling device controlled by one of the manipulative means to temporarily couple the normally ineffective actuating means with the operating mechanism; and means to prevent the uncoupling of the normally ineffective actuating means and the operating mechanism.

9. In a machine of the class described, the combination with operating mechanism; depressible keys; and means to detain the keys in their depressed positions; of normally ineffective means to actuate the key-detaining means to free the depressed keys; a plurality of manipulative means to control operation of the operating mechanism; a coupling device controlled by one of the manipulative means to temporarily couple the normally ineffective actuating means with the operating mechanism; and means also under control of the manipulative means to prevent the uncoupling of the normally ineffective actuating means and the operating mechanism.

10. In a machine of the class described, the combination with operating mechanism; depressible keys; and means to detain the keys in their depressed positions; of normally ineffective means to actuate the key-detaining means to free the depressed keys; a plurality of manipulative means to control operation of the operating mechanism; a coupling device controlled by one of the manipulative means to temporarily couple the normally ineffective actuating means with the operating mechanism; and means tripped by a second depression of the last-named manipulative means to prevent the uncoupling of the normally ineffective actuating means and the operating mechanism.

11. In a machine of the class described, the combination with operating mechanism; depressible keys; and means to detain the keys in their depressed positions; of normally ineffective means to actuate the key-detaining means to free the depressed keys; a normally ineffective coupling between the actuating means and the operating mechanism; a manipulative device to render the coupling effective for a single operation of the machine; and a second manipulative device controlled by the first-named manipulative device, and operable to render the coupling effective for successive operations.

12. In a machine of the class described, the

combination with operating mechanism; de-
pressible keys; and means to detain the keys
in their depressed positions; of normally in-
effective means to actuate the key-detaining
means to free the depressed keys; and sepa-
rate means to control the operating mecha-
nism, one only of which controlling means
renders effective the means to actuate the key-
detaining means.

10 13. In a machine of the class described, the
combination with operating mechanism; de-
pressible keys; and means to detain the keys
in their depressed position; of normally in-
effective means to actuate the key-detaining
means to free the depressed keys; a normally
ineffective coupling between the operating
mechanism and the means to actuate the key-
detaining means; separate means to control
the operating means; and means operable by
one only of the controlling means to render
the coupling means effective.

14. In a machine of the class described, the
combination with operating mechanism, de-
pressible keys; and means to detain the keys
25 in their depressed positions; of normally in-
effective means to actuate the key-detaining
means to free the depressed keys; a normally
ineffective coupling between the operating
mechanism and the means to actuate the key-
detaining means; separate means to control
30 the operating means; means normally oper-
able by one only of the controlling means, to
render the coupling means effective; and a
special key to render the coupling effective
35 during an operation of the machine initiated
by another of the controlling means.

15. In a machine of the class described, the
combination with operating mechanism; de-
pressible keys; and means to detain the keys
40 in their depressed positions; or normally in-
effective means to actuate the key-detaining
means to free the depressed keys; a normally
ineffective coupling between the actuating
means and the operating mechanism; a plu-
45 rality of independently operable means to
control the operating mechanism whereby to
effect operations of the machine; means inter-
posed between one of the independently oper-
able means and the coupling to render the
50 coupling effective; and a special manipula-
tive member operable upon the interposed
means to render the coupling effective irre-
spective of the independently operable means.

16. In a machine of the class described, the
55 combination with operating mechanism; de-
pressible keys; and means to detain the keys
in their depressed positions; of normally in-
effective means to actuate the key-detaining
means to free the depressed keys; a normally
60 ineffective coupling between the actuating
means and the operating mechanism; means
to control the operating mechanism to enable
an operation of the machine; means inter-
posed between the control means and the
65 coupling to render the latter effective; and a

detent to retain the control means in set po-
sition, and releasable by the means which
actuates the key detaining means for the keys.

17. In a machine of the class described, the
combination with operating mechanism; de-
pressible keys; and means to detain the keys
in their depressed positions; of normally in-
effective means to actuate the key-detaining
means to free the depressed keys; a normally
ineffective coupling between the actuating
means and the operating mechanism; means
to control the operating mechanism to enable
an operation of the machine; means inter-
posed between the control means and the
coupling to render the latter effective; a 70
special manipulative member operable upon
the interposed means to render the coupling
effective irrespective of the control means for
the operating mechanism; and a detent con-
trolled by the control means to retain the 75
special manipulative member in effective
position.

In testimony whereof I affix my signature.
PASCAL SBURLINO.
